HEAD FOR WELL CASINGS AND TUBINGS

Filed March 3, 1931

UNITED STATES PATENT OFFICE

WALLACE A. ROCKWELL, OF LONG BEACH, AND LAURENCE M. STANFIELD, OF WHITTIER, CALIFORNIA

HEAD FOR WELL CASINGS AND TUBINGS

Application filed March 3, 1931. Serial No. 519,854.

This invention relates to oil and gas wells and more particularly to the closing means between the casing strings, where more than one string is used, and between the casing 5 and tube, whereby a tight joint is maintained without the use of packing, and whereby blow outs are prevented.

While the drawing illustrates a preferred embodiment of the invention, it is to be understood that in adapting the means to meet specific needs and requirements, the design 10 may be varied and changes in the minor details of construction may be resorted to within the scope of the invention as claimed, without departing from the spirit thereof.

For a full understanding of the invention and the merits thereof, reference is to be had to the following description and the drawing hereto attached, in which:

20 Figure 1 is a sectional view of a casing and tubing head illustrative of an embodiment of the invention.

Figure 2 is an enlarged fragmentary sectional view.

25 Corresponding and like parts are referred to in the following description and designated in the several views of the drawing by like reference characters.

The numeral 1 designates the well tubing 30 and the numerals 2, 3 and 4 indicate strings of casing. A body member 5 is connected to the upper end of the outermost casing string 2 and its intermediate portion 6 flares to provide an inner tapered wall to coat with slips 35 (not shown) for holding the casing strings 3 when coupling the sections thereof. The upper portion of the body 5 is enlarged and internally threaded, as indicated at 7. The inner shoulder at the base of the enlarged 40 threaded portion 7 is stepped, as indicated at 8 and 9. A cap member 10 coacts with the body member 5 and is supported therein by means of an outwardly disposed flange 11 overlapping and resting upon the inner shoulder 8 of the body 5. The casing string 3 is connected to the cap 10 and the latter closes the space formed between the two casing strings 2 and 3. The cap member 10 is 45 of annular formation and its upper portion 50 is exteriorly reduced to form an outer shoul-

der 12 and is interiorly enlarged and threaded, as indicated at 14, to receive the lower end of a body member 15 similar in construction to the body member 5. A locking ring 16 comprising head and skirt portions is 55 threaded into the upper part of the body member 5. The head of the locking ring 16 engages the shoulder 12 of the cap member 10 and the upper end of the body member 5. The lower end of the skirt portion of the locking ring 16 engages the flange 11 and overlaps the shoulder 9. It is observed that the locking ring 16 positively engages the cap member 10 at two points 11 and 12, thereby securing said cap member against blow 60 out and assuring a tight joint without necessitating the use of packing.

The body member 15 is similar in structural details of the body member 5 and its lower end is reduced and externally threaded 70 to engage the threaded portion 14 of the cap member 10. The intermediate portion 17 of the body member 15 flares and the upper end is enlarged and interiorly threaded to receive the skirt portion of a locking ring 18 75 similar to the locking ring 16. The inner shoulder formed at the base of the threaded part 19 is stepped to accommodate the outer flange 20 of a cap member 21 and the overlapping end of the skirt portion of the locking ring 18. The upper portion of the cap member 21 is exteriorly reduced to provide a shoulder 22 and its inner portion is enlarged and screw threaded as indicated at 23. The casing string 4 is connected to the cap 80 member 21.

The casing head 24 has its lower end reduced externally and threaded to match the threaded portion 23 of the cap member 21. The upper end of the opening is enlarged and 85 threaded to receive a riser 25 to which is attached the tubing head body 26 which is substantially the same as the casing head bodies 5 and 15. The intermediate portion 27 of the body 26 is enlarged to provide an inner tapered wall adapted to coat with slips 90 in a manner well understood. The opening of the body 26 is enlarged at its upper end and interiorly threaded as indicated at 28, to receive the skirt portion of a locking ring 100

29. A cap or tubing head 30 is formed with an outer flange 31 and an outer shoulder 32 at the base of an upper reduced portion. The tube 1 is threaded into the cap or head 30 and the latter closes the space between said tube and the casing string 4. The head of the locking ring 29 engages the shoulder 32 and upper end of the body 26. The skirt portion of the locking ring 29 engages the flange 31 and overlaps the shoulder at the inner end of the threaded portion 28.
- It will be understood from the foregoing reference being had to the accompanying drawing, that blow out is prevented and tight joints assured without the necessity of using packing which is objectionable in the event of a fire. As indicated, the several bodies are tapped to provide outlets to which pipes may be connected for carrying off the air or gas, as the case may be.

What is claimed is:

1. A head for well casing and tubing comprising a body having its intermediate portion flared to provide an inner tapered wall, and having its upper portion enlarged and interiorly threaded, and having the inner shoulder at the base of the threaded portion stepped, a cap member within the upper portion of the head and formed with an outer flange to engage the inner stepped portion of the shoulder, and having its upper portion reduced to provide an outer shoulder, and a locking ring comprising a head and a straight portion, the head overlapping and engaging the outer shoulder of the cap and the upper end of the said body, and the lower end of the straight portion engaging the said outer flange and overlapping the upper stepped portion of the shoulder.
2. A head for well casing and tubing comprising a body having its intermediate portion flared to provide an inner tapered wall, and having the upper end of the opening enlarged and interiorly threaded and having the shoulder at the base of the threaded portion stepped, a cap member having its upper part exteriorly reduced to provide an outer shoulder and interiorly enlarged and threaded and provided adjacent its lower end with an outer flange to engage the inner stepped portion of the body, and a locking ring comprising a head to engage the outer shoulder of the cap and the upper end of the body and having its straight portion engaging the outer flange of the cap and overlapping the upper stepped portion of the inner shoulder.
3. In a well comprising several strings of casing and a tube, a plurality of similar bodies each having the intermediate portion thereof flared and the upper end enlarged and interiorly threaded and having the shoulder at the base of the threaded portion stepped, coaxing caps having upper shoulders and lower flanges, the latter engaging

the stepped shoulders, locking rings for securing the caps to the respective bodies comprising a head and a straight portion, the head engaging the outer shoulder of the cap and the upper end of the body and the skirt portion engaging the outer flange and overlapping the stepped shoulder, and a member fitted to the topmost cap and connected to the tubing head body.

In testimony whereof we affix our signatures.
